B. B. BRODFUEHRER

PROCESS OF SHOE MANUFACTURE

Filed Oct. 26, 1923

UNITED STATES PATENT OFFICE.

BISMARCK BARON BRODFUEHRER, OF CINCINNATI, OHIO, ASSIGNOR TO THE LOUIS G. FREEMAN COMPANY, OF CINCINNATI, OHIO, A CORPORATION OF OHIO.

PROCESS OF SHOE MANUFACTURE.

Application filed October 26, 1923. Serial No. 670,865.

My present invention relates to the manufacture of boots and shoes and is directed to improve the making, fitting, lasting and finishing of shoes having openwork parts or sections in the quarter, vamp or other portion of the upper materials. In the manufacture of shoes, particularly ladies' low cut shoes, pumps, slippers, and the like, wherein a portion or portions of the upper are 5 cut out, for ornamentation, lightness or design, it has been necessary heretofore to cut out these parts of the upper materials while the same were flat. During the lasting operation, that part of the shoe adjacent to the 10 cut out portions, would be distorted during lasting. As the lasting operation is relied upon to secure the fitting of the upper materials and it is essential that the lasting operation take out the surplus "stretch" in 15 the leather, it will be appreciated that a considerable variation in the stretching, during lasting, adjacent the cut out portions, would result. In fact the lasting would so distort 20 and change the shape of the entire shoe upper materials, where cut out portions are employed, that it has been extremely difficult 25 to make such shoes, unless the lining was left uncut, and then it was a difficult hand operation to cut out the lining. Also the 30 lining, if of canvas or a different grade of leather than the upper, would stretch unevenly.

My invention is directed to obviate the difficulties heretofore experienced in this 35 class of work, and to insure the lasting of shoes with the cut out portions, both through upper and lining, as easily, readily, expeditiously and speedily, without danger of distorting or changing the same, as was formerly 40 done in solid vamp and quarter shoe structures.

My invention contemplates the reinforcing 45 of the shoe upper materials adjacent to the cut out portion, thus enabling the lasting operation to be performed without difficulty along the sides of the shoe where the cut out portions occur. Such reinforcements may 50 be applied inside the lining, between the lining and upper, or outside of the shoe, and can remain within the shoe upper and on the last until the soling, heelng and finishing operations are all completed. With the final removal of the last from the shoe, the reinforcement can be removed.

In carrying out my invention I may em-

ploy a layer of canvas, paper, composition or other suitable material as the reinforcing, and can either attach the same about and around the cut out portions by adhesive or other means preferably permitting subsequent easy removal. This reinforcement may be of sufficient extent to be grasped by the lasting pincers, and therefore aid in taking up the stretch and strain of the lasting operations; or the reinforcement may be simply 60 applied about the portions to be reinforced, and extend downwardly a less distance than the side of the upper to the insole. Furthermore this reinforcement may be applied either internally or externally of the shoe, 65 and in either event can remain in the shoe until it is completed, finished and treed, and the last finally removed.

I preferably apply the reinforcement layer or layers about the openings in the cut out 70 portions on the interior of the shoe upper prior to assembling same on the last, and then leave these reinforcements within the shoe through the various processes of shoe manufacture. A further advantage is secured 75 in this way, as the reinforcement will prevent the inking stains, finishing colors and dressings, from working through the openings in the cut out portions to the interior of the shoe and thus prevent damaging 80 of the linings, as well as keeping the last clean.

Further features, important advantages, and details will be hereinafter more fully pointed out and claimed.

Referring to the drawings, illustrating a preferred embodiment of the invention,

Fig. 1 is a side view of an upper showing a typical cut out portion in the quarters and vamp;

Fig. 2 is a view partly in cross-section illustrating my method of applying reinforcing;

Fig. 3 is a cross-sectional view on the line 3-3 of Fig. 2;

Fig. 4 is a cross-sectional view showing the upper, reinforcements, insole and outsole assembled on the last, illustrating typical McKay shoe manufacture; and

Fig. 5 is a side view of the completed shoe 105 with the reinforcements removed.

It will be appreciated that while I have shown in one of the figures above noted, a McKay shoe construction, that the present process is of equal importance, desirability 110

and advantage in connection with any of the standard methods of shoe manufacture, such as welt shoes and turn shoes, wherever open-work or cut out portions of the upper, vamp, 5 quarters, foxings or the like, are employed. In the particular shoe shown for illustrative purposes in the drawings, the upper materials comprise the vamp 1, quarters 2, lining 3, and show a typical design of open-work or cut out portions, consisting in the cut sections 5, 6, 7, and 8 of each quarter, leaving the resulting straps or sections 9, 10, 10 11, 12 and 13. It is that portion of the shoe quarters adjacent the cut out sections 5, 6, 15 7 and 8, and the corresponding straps which is distorted during lasting and which distortion I prevent by my novel invention of applying a reinforcing at this part of the shoe. As herein shown I apply a layer consisting 20 of a sheet of material, preferably adhesive, 15, which may extend from the top strap portion 9 entirely across the cut out sections to the forward strap portion 13, and into the open vamp portions, if desired, and downwardly, either to a position substantially adjacent the insole 20 or substantially co-extensive with the bottom edge of the upper materials and lining 3. In the latter instance 25 the reinforcing 15 will be engaged by the lasting pincers during the lasting operation and thus prevent undue straining and distortion of the cut out portion. It is, however, equally feasible to provide the reinforcing layer and unite it, preferably by any 30 suitable adhesive, simply covering the cut out portions and a substantial area of the adjacent upper, this being indicated at the dotted line 16, Fig. 2.

With the reinforcing material thus applied, the upper is then assembled on a last 40 21, see Fig. 4. The insole 20 is applied, the shoe lasted, and the outsole 22 affixed, and the stitching operation completed. As explained, my process is equally applicable to 45 welt, turn, McKay or other standard shoe manufacturing processes, Fig. 4 illustrating its adaptability to a McKay shoe construction, showing the shoe in lasted position and just prior to removal of the last and attaching the stitching.

The layers 15 preserve and protect the cut out portion of the upper, holding the remaining strap-like members in a proper alignment and position, keeping them 55 smooth, and preventing wrinkling, and thus preserving the design of the shoe accurately throughout. No special care during the lasting need be taken, and the resulting shoe is completed, the inking, finishing stains, etc., 60 being prevented from working into the lining through the open sections, and after the removal of the last the reinforcing pieces 15 can be instantly and readily taken out. I believe that my method of thus preserving, 65 by suitable reinforcements, the cut out por-

tions of shoe uppers, is a distinct novelty in this art, and I wish to claim the same herein broadly.

My invention is further described and defined in the form of claims as follows:

1. The improved process of manufacturing shoes, which consists in reinforcing the shoe uppers, assembling the reinforced upper materials on a last with the reinforcing material in engagement with the last, lasting, completing the shoe and thereupon removing the reinforcement. 70

2. The improved process of manufacturing shoes having cut out portions in the upper, which consists in reinforcing the shoe uppers adjacent said cut out portions, assembling the reinforced upper materials on a last with the reinforcing material between the upper and the last, lasting, completing the shoe and thereupon removing the reinforcement. 80

3. The improved process of manufacturing shoes, which consists in applying reinforcing material to a predetermined part of the shoe upper to prevent distortion of the shoe upper during lasting, and assembling the reinforced upper on a last with the reinforcing material between the upper and the last, lasting and completing the shoe, and thereupon removing the reinforcing material. 90

4. The improved process of manufacturing shoes, which consists in applying reinforcing material to a predetermined part of the shoe upper interior, by adhesive, said material and adhesive being of sufficient strength to prevent distortion of the shoe upper to which it is applied during the lasting and subsequent shoe manufacturing processes and then removing the reinforcing material. 100

5. The improved process of making boots and shoes having cut out portions in the upper, which consists in applying to the cut out portions of the upper reinforcing material, leaving said material so applied to the upper during the processes of shoe manufacture and so positioned as to be between the upper and last during the lasting operation, and removing said material from the shoe after the completion of manufacturing the same. 110

6. The process of making shoes having cut out upper portions, which consists in applying a removable reinforcing layer to the insides of the shoe upper, so positioned and arranged as to prevent distortion of the cut out portion during the processes of shoe manufacture, said reinforcing material being attached to the cut out portion at a plurality of points, assembling, lasting and completing the shoe and thereafter removing the reinforcing from the inside of the completed shoe. 120

7. The improved process of manufactur-

- ing shoes, which consists in cutting out a decorative design on a predetermined portion of the upper, applying reenforcing material to the interior of the upper around the 5 cut out design, securing the reenforcing material to the upper, lasting the shoe while maintaining the reenforcing material in position, and then completing the manufacture of the shoe.
- 10 8. The improved process of manufacturing shoes which have decorative designs cut out on a predetermined portion of the upper, which consists in first performing the decorative cutting out action associating with 15 such upper a lining, and reenforcing material, lasting the shoe while maintaining the remaining reenforcing material in po-
- sition, and then completing the manufacture of the shoe.
9. The improved process of manufacturing boots and shoes, having openwork cut out portions apt to be distorted during lasting, including the step of applying to the upper, reinforcing material of substantially greater area and extent than the shoe portion apt to be distorted, maintaining said material in position during lasting, and relying upon the reinforcing material to prevent distortion of the cut out portion during said lasting operation. 20 25 30

In testimony whereof, I have signed my name to this specification.

BISMARCK BARON BRODFUEHRER.
